Giuseppe Tavolazzi, Como, Italy, assignor to
Tavolazzi & Fumagalli, Milan, Italy, a firm of
Italy

Application February 25, 1953, Serial No. 23,777

Term of patent 7 years

(Cl. D58—13)

To all whom it may concern:

Be it known that I, Giuseppe Tavolazzi, a citizen of Italy, residing at Missaglia, Como, Italy, have invented a new, original, and ornamental Design for a Toolbox, of which the following is a specification, reference being had to the accompanying drawing, forming a part hereof.

In the drawing:

Figure 1 is a top perspective view of a toolbox in closed position, showing my new design; and

Fig. 2 is a top perspective view of the open toolbox shown in Fig. 1, the cover being removed.

The sides of the box not shown are the same as those shown.

I claim:

The ornamental design for a toolbox, as shown and described.
